UNITED STATES PATENT OFFICE.

SAMUEL W. OSGOOD, OF CHICAGO, ILLINOIS.

DESIGN FOR A LAMP-LENS.

45,724.

Specification for Design.

Patented May 5, 1914.

Application filed March 6, 1914. Serial No. 823,027. Term of patent 14 years.

To all whom it may concern:

Be it known that I, SAMUEL W. Osgood, a citizen of the United States, residing at Chicago, in the county of Cook and State of Illinois, have invented a new, original, and ornamental Design for Lamp-Lenses, of which the following is a specification, reference being had to the accompanying drawing, forming a part thereof.

Figure 1 shows a front elevation of my lamp lens; Fig. 2 is a plan view of the lens

shown in Fig. 1, and Fig. 3 is a sectional view of the lens shown in Fig. 1 taken along the line 3—3.

I claim:

The ornamental design for a lamp lens, as shown.

SAMUEL W. OSGOOD.
